UNITED STATES PATENT OFFICE.

ADELARD E. RAVENELL, OF NORWICH, CONNECTICUT.

LOOM WEAVE-LINE INDICATOR.

Application filed February 6, 1923. Serial No. 617,318.

To all whom it may concern:

Be it known that I, ADELARD E. RAVENELL, a citizen of the United States, residing at Norwich, in the county of New London and State of Connecticut, have invented certain new and useful Improvements in Loom Weave-Line Indicators; and I do hereby declare the following to be a full, clear, and exact description of the invention, such as will enable others skilled in the art to which it appertains to make and use the same.

This invention relates to a loom weave line indicator and it generally aims to improve a device of this character and particularly the form disclosed in Letters Patent No. 1,409,778, issued to me on March 14, 1922.

Another object is to provide a construction adapted for more universal attachment to the various types of looms in use and one which may be fastened to the loom frame pursuant to this end as distinguished from independent support like the disclosure in said patent.

25 A further object is to provide a construction having a novel mounting bracket for the active mechanism.

A still further object is to provide a form having novel means to prevent actuation of the loom while the gaging mechanism is in operative position.

One more object is to provide a novel construction of gage.

Various additional objects and advantages will become apparent from a consideration of the description following taken in connection with accompanying drawings illustrating one operative embodiment.

In said drawings:—

40 Figure 1 is a perspective view illustrating the invention as applied to a loom, the latter being shown fragmentarily;

Figure 2 is a vertical sectional view taken substantially on line 2—2 of Figure 1;

45 Figure 3 is a vertical sectional view on the line 3—3 of Figure 1;

Figure 4 is a horizontal sectional view on the line 4—4 of Figure 1;

50 Figure 5 is a cross sectional view on the line 5—5 of Figure 1;

Figure 6 is a detail perspective view of the lock collar used on the operating shaft, and

55 Figure 7 is a sectional view taken on the plane indicated by the line 7—7 of Figure

2, looking in the direction indicated by the arrow.

Referring specifically to the drawings, the frame of a loom is fragmentarily suggested at A of which the breast beam is designated B.

A justifying mechanism is provided as generally designated 10 which is adapted to be moved into the plane of the fabric as required in determining the position of the 65 weave line in the resetting of the woven portion of the fabric after an interruption of the operation of the loom and thus to accomplish the same function as the device of my said Patent No. 1,409,778. This 70 mechanism has a bracket 11 provided with an arm 12 which may be integral therewith. A gage arm 13 is pivoted as at 14 to an arm 15 of bracket 10. At the upper end, gage 13 has spaced offset blades 16 adapted to be 75 projected upwardly between the warped thread and the cloth being woven. The lower end of gage 13 is enlarged as at 17 to constitute a weight. Said weight has a vertical elongated slot 18 into which the crank 19 of a shaft 20 loosely extends. Shaft 20 is journaled through a depending arm 21 of bracket 15 and on one side thereof has a spacing sleeve 22 mounted as shown. Fas- 80 tened to shaft 20 on the other side of arm 21 85 is a depending arm 23 rigid therewith. A pointer or indicator 24 is pivoted on shaft 20 and has a screw rod 25 pivoted to its lower end as at 26. Screw rod 25 passes loosely through a guide sleeve 27 pivoted 90 at 28 on the arm 23. A nut 29 is adjustable on rod 25 so as to vary the permissible position of said indicator 24. A coil spring 30 surrounds shaft 20 and is fastened to indicator 24 and arm 23 so as to urge the indicator to such a position as to draw the nut 29 into contact with arm 23. Indicator 24 coacts with a dial or plate 31 which is preferably provided with a normal or unit mark or indication as at 32. In normal position, 95 the edges of the blades 16 are adapted to lightly touch with the weave line of the fabric similar to the blades 24 in the construction of my said Patent No. 1,409,778. The

100 normal position of indicator 24, due to weight 17 is vertical. Any deviation of said indicator 24 from the vertical may be indicated to the operator upon reference to the indicator relative to indication 32. If the weave line is too far back and is out of con- 105 110

tact with the edges of the blade 16, this fact may be readily determined by a slight swinging movement of the gage arm. When the edges of the blade are in light contact with the weave line and the pointer is directed to the unit or neutral mark 32 of the dial, the weaver will know that the fabric is in proper position to resume the operation of the loom without possibility of producing a lay mark.

The said weave line indicator or gaging means in Figure 1 is shown in operative position in full lines and in inoperative position in dotted lines, being movable by appropriate means from one position to the other. The attaching arm 12, by means of an elongated slot 33 therein and a set screw 34, may be adjustably and extensibly connected to an arm 35 thickened or otherwise weighted as at 36.

A substantially U-shaped attaching bracket 37 is fastened to the breast beam B as by means of screws 38 penetrating said beam and passed through an elongated slot 39 in said bracket. Said bracket 37 has a top lug or plate 40 and a bottom lug or plate 41. Spaced vertically disposed guide rods 42 are fastened at opposite ends to said plates 40 and 41 and passed through suitable conical openings 43 in the arm 35. Plate 35 is thus slidable along said arms so that it may occupy its inoperative position as suggested in dotted lines and also its operative position as shown in full lines. In its operative position, the device is adapted to be held against downward displacement by the frictional or wedging engagement of bushings, preferably conical as shown at 44 and located at the upper end of rods 42.

An operating arm 45 is provided to lift the device from the idle to utile position and also to force said plate 35 out of frictional engagement with the bushing 44. Arm 45 at its manipulating end may have a hook shaped handle 46. At its other end, it is pivoted to the plate 35 by a pin 47. A suitable slot at 48 is provided through bracket 37 in order to provide clearance for manipulation of the rod 25.

The operating handle or lever for the loom is shown at C and is rigid with an operating shaft D journaled on the frame A. It will be realized that as is usual in a loom, the operation of shaft C from the full line or idle position to the dotted line position places the necessary parts of the loom in gear and causes operation thereof. On shaft D is a lock collar 50 which may comprise a plurality of semi-circular sections 51 fastened together as by screws at 52 and rigidly clamped to shaft D by a set screw 53 passing through one of the sections 51. A lug 54 projects from one of the sections 51 and is adapted to coact with

the hook end 55 of a detent pawl or lever 56 which is pivoted by a pin 57 to a plate 58 secured to the bracket 37. Detent 56 is relatively long so that the hook end 55 will seek engagement with the lug 54 to restrain movement of shaft D by manipulation of the lever C.

A trip member for the detent 56 is provided as at 59 and may be a rod having one end 60 extended loosely through an opening in lever 56 and fastened as by a cotter pin or the like 60. The other end of member 59 may be a laterally offset lug 61 disposed over and in spaced relation above the plate 41 in the locked position of said pawl or lever 56. Thus when the indicating or gaging means 10 is in its elevated or utile position, lever 56 and collar 50 are engaged and thus the lever C and shaft D cannot be operated. However when said mechanism 10 is in its idle position as shown by the dotted lines, the weighted portion 36 engages the lug 61 moving it downwardly against the plate 41 and causing the trip member 59 to elevate the lever 56 at the end 55, thereby disengaging the collar 50 and remaining out of engagement therewith so that the machine may be freely operated while the mechanism 10 is in utile position.

As merely one embodiment has been illustrated, it is to be understood that various changes in the details, combination and arrangement of the parts may be resorted to provided the same fall within the spirit and scope of the invention.

I claim as my invention:

1. A weave line indicator having a gage member, a shaft member, one of said members having an elongated slot, the other of said members having a crank extending into said slot, and indicating means operable by said shaft.

2. A weave line indicator including a bracket, a gage member pivoted thereto and weighted, a shaft member journaled on said bracket, said shaft member having a crank, a gage member having an elongated slot into which said crank extends, an indicating means including an indicator member mounted by said shaft.

3. A weave line indicator having a gage member, a shaft member, one of said members having an elongated slot, the other of said members having a crank extending into said slot, an arm depending from said shaft, an indicator pivoted on said arm, and an adjustable connection between said arm and said indicator.

4. A weave line indicator having a gage member, a shaft member, one of said members having an elongated slot, the other member having a crank extending into said slot, an arm extending from said shaft, an indicator pivoted on said arm, a sleeve piv-

oted on said arm, a screw rod loosely passing through said sleeve and pivoted to said indicator, a nut on said screw rod to abut said arm, and a spring surrounding said 5 shaft and connected to said arm and indicator to maintain said nut in engagement with said arm.

5. In a weave line indicator, gaging mechanism, means to mount said mechanism for 10 movement to and from operative position, and means having friction tight fit with said mechanism to maintain the latter in operative position.

6. In a weave line indicator, gaging mechanism, means to mount said mechanism for 15 movement to and from operative position including a rod along which said mechanism slides, said mechanism having a conical recess, and said rod having a conical portion 20 adapted for friction tight fit in said recess to maintain said mechanism in operative position.

7. In a weave line indicator, gaging mechanism, means to mount said mechanism for 25 movement to and from an operative position, and an actuating arm for said mechanism pivoted thereto, said arm being adapted to lie in a substantially horizontal position on a part of the loom when the gaging 30 mechanism is in an operative position.

8. In a weave line indicator, gaging mechanism, a bracket attachable to a loom having spaced plates, a rod spanning said plates, said gaging mechanism being movable along 35 said rod.

9. In a weave line indicator, gaging mechanism, a bracket attachable to a loom having spaced plates, a rod spanning said plates, said gaging mechanism being movable along 40 said rod, means on said rod for wedging coaction with said gaging mechanism to posi-

tion the latter in operative position, and operating means for said mechanism pivoted thereto.

10. In a weave line indicator, a bracket 45 attachable to a loom, said bracket having spaced plates, rods spanning said plates, an arm slidably mounted on said rod, gaging mechanism carried by said arm, one of said rods adjacent the uppermost plates having a 50 bushing of substantially conical form thereon, said bushing adapted for wedging coaction with said plate.

11. In a weave line indicator, gaging mechanism, means to mount said mechanism 55 for movement to and from an operative position, and means controlled by said gaging mechanism to prevent operation of a loom while said gaging mechanism is in operative position. 60

12. In a weave line indicator, gaging mechanism movable to and from an operative position, means to prevent operation of a loom while said gaging mechanism is in operative position, and said means being 65 actuated into inoperative position by movement of said gaging mechanism into inoperative position.

13. In a weave line indicator, a gaging mechanism, mounting means for said mechanism, a detent member to prevent operation of a loom while said mechanism is in operative position, a trip member for said detent, and said trip member being arranged 70 in the path of movement of said mechanism 75 to inoperative position.

In testimony whereof I affix my signature in presence of two witnesses.

ADELARD E. RAVENELL.
